UNITED STATES PATENT OFFICE.

PAUL JOLLEY, OF CONRAD, MONTANA.

AUTOMATIC DRINKING-FOUNTAIN.

1,120,940.

Specification of Letters Patent.

Patented Dec. 15, 1914.

Application filed January 2, 1912, Serial No. 663,899. Renewed May 19, 1914. Serial No. 839,643.

To all whom it may concern:

Be it known that I, PAUL JOLLEY, a subject of the Emperor of Germany, residing at Conrad, in the county of Teton and State of Montana, have invented certain new and useful Improvements in Automatic Drinking-Fountains, of which the following is a specification.

This invention relates to improvements in automatic drinking fountains adapted for the use of chickens, cattle or the like.

The principal object of the invention is to provide a fountain for the purpose described which is provided with a plurality of drinking tanks adapted to be automatically filled from the reservoir.

Another object of the invention is to provide a drinking fountain of the character described in which the drinking tanks are each provided with a hinged cover and weighted platforms pivotally mounted upon the frame and connected to the covers for actuating the same by the weight of a fowl or animal upon said platform.

A further object of the invention is to provide a fountain of the character described in which the parts are detachably mounted, so that any one of said parts may be readily removed and replaced whenever so desired.

A still further object of the invention is to provide a fountain of the character described which consists of a minimum number of parts, is therefore simple in construction, and is cheap to manufacture.

With these and other objects in view, the invention consists in the construction and novel combination of parts hereinafter fully described, illustrated in the accompanying drawings, and pointed out in the claims hereto appended; it being understood that various changes in the form, proportion, size and minor details of construction within the scope of the claims, may be resorted to without departing from the spirit or sacrificing any of the advantages of the invention.

In the drawings: Figure 1 is a side elevation of a fountain constructed in accordance with my invention, Fig. 2 is a top plan view thereof, Fig. 3 is a plan view of the supporting frame showing the platforms pivotally mounted thereon, Fig. 4 is an enlarged vertical sectional view taken on the line 4-4 of Fig. 2, Fig. 5 is a horizontal sectional view taken on the line 5-5 of

Fig. 1, Fig. 6 is a detail sectional view of the frame.

Like reference numerals designate corresponding parts in all the figures of the drawings.

Referring to the drawings, the invention comprises a frame which consists of an annulus, designated as a whole by the reference letter A. This annulus comprises a plurality of arcuate sections 5, the adjacent ends of adjacent sections being respectively connected by means of hinges 6, each hinge including a pair of leaf-sections 8-8, which are detachably connected by a pin 9. It will thus be observed that these sections 5 can be readily disengaged one from the other whenever so desired. Centrally formed in each arcuate section 5 is a transverse opening 10, and disposed within each opening is a tongue 12 of an inwardly extending radially disposed frame section 13, the inner ends 14 of said radial sections being disposed equidistant from the annulus, and spaced from each other to form a central hollow portion. Disposed between each adjacent pair of radial sections 13 is an arc-shaped platform 15, the inner edges 14 of said sections 13 projecting inwardly beyond the inner edges 16 of said platform. Each platform is formed adjacent its outer edge 17 with a weight 18, and each platform is provided on its underface at each end intermediate the weight 18 and inner edge 14 with bearings 19-19 for respectively receiving pintles 20 carried by adjacent radial sections 13, said pintles being of course transversely disposed with respect to said sections. It will thus be observed that by means of the weights 18, the platforms are normally held in a horizontal plane, and the inner edges 16 thereof are prevented from upward movement by means of stop pins 21 carried by the respective sections 13. A wire 22 is disposed in spaced relation to the inner edge 16 of each platform, and has its ends 23-23 bent outwardly at right angles and connected to said platform by solder or other suitable means. The central portion of the wire is bent outwardly in the form of a V, as indicated by the reference character 24.

My invention further comprises a substantially semi-spherical hollow water receptacle, indicated as a whole by the reference numeral 25. This receptacle includes a circular bottom 26 and a dome-shaped top 27,

said top being centrally formed with an opening having a depending wall 28 which terminates at its lower end in an inwardly extending flange 29 constituting a seat. Depending from the bottom 26 in spaced relation to the periphery thereof is a vertical flange 30. Formed in the top 27 at a suitable distance above the bottom 26 is a plurality of pairs of discharge openings 31-31, said openings being all disposed in the same horizontal plane, and each pair of openings being respectively disposed centrally with respect to a platform 15. Exteriortly secured to the top 27 around each opening is a drinking tank 32, and associated with said tank is a closure 33 which is connected to the top 27 by hinges 34-34, whereby said closure may be readily swung upwardly. Each pair of the closures 33 is connected by a cross bar 35, and each cross bar is centrally formed with an eye 36. It is to be observed in this connection that there are as many pairs of drinking tanks 32 as there are platforms. Curved pipes 37 have one end 38 projecting through the top 27 at a point above a respective eye 36, and has its other end 39 projecting through the bottom 26. This water receptacle 25 is adapted to be centrally seated within the platform in such a manner that the periphery of the bottom 26 will be seated upon the inner ends 14 of the radial sections 13. Suitable vertical slots are formed in the flange 30 to receive said inner ends 14 of the sections 13 and the end portions 23 of the wires 22. A flexible connection 40 is disposed within each pipe 37, and one end thereof is connected to the eye 36 of a respective cross bar 35 and the other end is connected to the apex of the V-shaped portion 24 of a wire 22. It will thus be observed that as the fowl or animal places himself on the inner end of any of the platforms 15, the said inner end will be depressed, and through the medium of the wire 22 and the flexible connection 40, the closures 33 of the drinking tanks 32 will be elevated. As soon as the fowl or animal steps from the platform, the weight 18 thereof will immediately return said platform to its normal position. At the same time the weight of the covers 33 will be sufficient to return the flexible connection 40 to its position ready for the next operation.

My invention further comprises a water reservoir designated as a whole by the reference numeral 41. This reservoir comprises a cylindrical body 42 having an open top 43, said top being adapted to be closed by a detachable cover 44. The other or lower end of the body 42 is closed by an inverted hollow conical head 45 forming a consequent circular shoulder 46 adjacent the body 42. This head is formed at its apex with a small discharge opening 47, which is disposed in a plane slightly above the lower edge of the

openings 31 of the receptacle. The body 42 is furthermore formed with one or more exteriorly extending nipples 48 adapted for connection to a hose or the like, whereby the water in the reservoir may be readily replenished. Formed in the top 44 is a plurality of openings 49 adapted to form a vent for the reservoir, and these openings are adapted to be closed by a cover 50 which is pivotally connected, as at 51, to the cover 50 for swinging movements. The reservoir 41 is adapted to be seated within the wall 28 of the water receptacle and the shoulder 46 is adapted to engage the flange 29, and thereby support said reservoir.

From the foregoing, it will be observed that water from the reservoir 41 will be discharged through the opening 47 into the receptacle 25. This water will rise until the opening 47 is sealed, the water line being sufficiently high to permit of water entering the water tanks 32. As a result, the water within the tanks 32 will always remain at a constant level.

What is claimed is:

1. In an automatic drinking fountain, the combination with a supporting frame including an annulus and a plurality of inwardly extending radial sections, of a platform supported between an adjacent pair of sections for tilting movements, a water receptacle supported by said sections and formed with a discharge opening, a drinking tank supported exteriorly of the receptacle and communicating with the discharge opening thereof, a swinging closure for the tank, a water reservoir supported by the receptacle and having a discharge opening disposed within the receptacle and in a plane above the lower sides of the discharge openings of said receptacle, and a connection between the platform and the closure for raising the latter upon movement of the former.

2. In an automatic drinking fountain, the combination with a supporting frame including an annulus and a plurality of inwardly extending radial sections, of a platform supported between an adjacent pair of sections for tilting movements, a water receptacle supported by said sections including a bottom and a dome-shaped top, said top being formed with a discharge opening above the bottom, a drinking tank supported exteriorly of the top and communicating with the discharge opening thereof, a swinging closure for the tank, a pipe disposed within the receptacle and communicating with the bottom thereof and with the top at a point above the closure, a water reservoir supported by the receptacle and having a discharge opening disposed within the receptacle and in a plane above the lower sides of the discharge openings of said receptacle, and a flexible connection disposed within

the pipe and having one end connected to the closure and the other end to the platform for raising the former upon movement of the latter.

3. In an automatic drinking fountain, the combination with a supporting frame including an annulus and a plurality of inwardly extending radial sections, of a platform supported between an adjacent pair of sections for tilting movements, a water receptacle supported by said sections including a bottom and a dome-shaped top, said top being formed with a pair of discharge openings above the bottom, drinking tanks supported exteriorly of the receptacle and respectively communicating with said discharge openings thereof, a swinging closure for each tank, a cross bar connecting said closures, a pipe disposed within the receptacle and communicating with the bottom thereof and with the top at a point above said cross bar, a water reservoir supported by the receptacle and having a discharge opening disposed within the receptacle, said opening being formed in a plane above the lower sides of the first named discharge openings, a flexible connection disposed within the pipe and having one end connected to the cross bar and the other end to the platform for raising the former upon movement of the latter.

4. In an automatic drinking fountain, the combination with a supporting frame consisting of an annulus comprising a plurality

of separable arcuate sections and a plurality of radial sections respectively extending centrally from each arcuate section of the annulus, the inner ends of said radial sections being equi-distant from the annulus and from each other to form a central hollow portion, a platform supported between each adjacent pair of radial sections for tilting movements, weights respectively connected to the outer edges of said platform, stop pins carried by each radial section for normally holding said platforms in a horizontal plane, a water receptacle supported by said sections and formed with discharge openings respectively disposed in register with the platforms, drinking tanks supported exteriorly of the receptacle and respectively communicating with the discharge openings thereof, a swinging closure for each tank, a water reservoir supported by the receptacle and having a discharge opening disposed within a receptacle and in the plane above the lower sides of the discharge openings of the receptacle, and a connection between each platform and respective closure for raising the latter upon movement of the former.

In testimony whereof I affix my signature, in the presence of two witnesses.

PAUL JOLLEY.
